CLAIM

The ornamental design for an armrest support for a chair, as shown and described.

DESCRIPTION

This application is related to design patent application Ser. Nos. 29/305,602; 29/305,605; 29/305,606; 29/305,607; 29/305,610; 29/305,612; and 29/305,615, which are filed concurrently herewith.

FIG. 1 is a perspective view showing the front, left, and top of two armrest supports for a chair showing my new design, the broken lines of a chair being for illustrative purposes only and forming no part of my design;

FIG. 2 is a top plan view of one such armrest support for a chair;

FIG. 3 is a left side elevational view thereof;

FIG. 4 is a front elevational view thereof; and,

FIG. 5 is a bottom plan view thereof.

The right side and rear elevational views of the armrest support for a chair are similar to the left side and front, respectively, given that the helical coil shown is viewed from opposite directions.

The characteristic feature of the design resides in the application of a part having the appearance of an automotive shock absorber to the armrest support for a chair.
